UNITED STATES PATENT OFFICE.

GUSTAV A. ONCKEN, OF JACKSON, MICHIGAN.

STAVE-CUTTING MACHINE.

SPECIFICATION forming part of Letters Patent No. 423,626, dated March 18, 1890.

Application filed December 6, 1889. Serial No. 332,757. (No model.) Patented in Germany March 9, 1889, No. 48,663.

To all whom it may concern:

Be it known that I, GUSTAV A. ONCKEN, a citizen of the United States, residing at Jackson, Michigan, have invented an Improvement 5 in Stave-Cutting Machines, (for which I have obtained Letters Patent in Germany, No. 48,663, March 9, 1889,) of which the following is a specification.

In the accompanying drawings, forming 10 part of the specification, the same letters of reference denote corresponding parts.

The invention relates to a machine by the aid of which barrels, casks, and the like cooper's work can be made of one board of wood, 15 which is produced by peeling it from a log of wood rotating round its axis. The board, coming still wet from the peeling or rotating veneer-cutting machine, is of a width equal to the height of the barrel and of the required 20 thickness. It is cut in lengths corresponding to the circumference of the barrel.

By the machine, forming the object of the present invention, wedge-shaped pieces are 25 cut out of the board alternately at the two length sides in such way that the bases of all these pieces coincide with the two length sides. The board is then bent to form a cylinder. The stave-like pieces of both ends of it are forced to inward and kept together by 30 hoops, whereafter the barrel is finished.

In the drawings, Figure 1 is a front elevation of the machine, partly in section. Fig. 2 is a vertical cross-section. Fig. 3 shows the under die. Figs. 4 and 5 are a cross and a 35 length section of one plunger with upper die attached. Figs. 6 and 7 show the shape of the cut just when the board has been perforated and when it is straightened again. Fig. 8 represents a board after it has passed the machine.

The different parts of the machine are arranged between and supported by two frames A A. The shaft *a*, driven by means of the pulley *a'*, transfers its rotation to the double 45 crank-shaft *d* on top of the frames A A by means of a chain running over the chain-wheel *b* upon the shaft *a* and the chain-wheel *c* upon the crank-shaft *d*. The purchase of *b* and *c* is as 1 to 2. With the cranks *f* and *g* arranged 50 opposite each other are connected by the links *h* the plungers *k* and *l*, guided by the projections *k' l'* of the box-shaped cross-beam *m*.

At the under side of the said plungers *k* and *l* are fixed exchangeably the upper cutting-dies *x x'*. The lower dies *t' t''* are mounted in a suitable groove *t'* of the die-holder *t*, which is supported by the frames A A. The die-holder *t* is, for its whole length convex, so that its sides are sloping down a little to the roller-pairs *rr'* and *ss'*, which find their bearings in the frames A A, and of which the top rollers *r'* and *s'* are adjustable. These said rollers serve to feed the board between the dies and to remove it out of the machine. Two adjustable cheek-plates *u* and *v* keep 60 the board close to the under die and to the convex die-holder *t*. It is understood that the upper dies *x x'* cut alternately, as the cranks *f* and *g* are on opposite sides of their shaft *d*. Therefore the incisions will alternate, as in Fig. 8, and the feeding of the board must take place when the cranks stand at about half-stroke, and the rollers *rr'* and *ss'* must work simultaneously only at this time. That is effected in the following manner: Upon 65 the shafts of the rollers *r* and *s* are mounted two wheels *q q'* gearing into the pinion *p* upon the counter-shaft *p'*. Upon this shaft *p'* is mounted a grooved friction-pulley *o*, which is moved for a short time at each revolution of 70 the shaft *a* by the corresponding friction-wheel *n*, which is mounted upon the shaft *a*. This latter wheel *n* is furnished with the friction-ridges *n'*, corresponding to the grooves of the pulley *o* only for a short distance of the 75 periphery, so that it actuates the pulley *o* only when these ridges *n'* come in contact with the pulley *o*. Therefore the diameter of the chain-wheel *b* is to be about half as large as that of the chain-wheel *c* and the purchase of the 80 wheels *p* and *q q'* is also as 1 to 2. In case the cuts in the board shall be wider or narrower from each other the purchase of the chain-wheels is to be altered correspondingly.

The reason why the die-holder *t* is made 85 convex and why the board to be cut is bent correspondingly during the cutting manipulation is to make the openings in the board when it is straightened, Figs. 6 and 7, wider on the under side than on the upper side, 90 which latter forms afterward the outside of the barrel. By this means the sides of the cuts make tight joints when the board is bent together and the stave-like pieces of 95 100

the board are forced together to give to the barrel the proper bulged shape. For different shapes and sizes of barrels corresponding dies must be used and the rollers $r' s'$ and 5 cheek-plates $u v$ accordingly adjusted.

After having described my invention, and the manner in which the machine works, I claim as new—

1. In a machine for cutting wedge-shaped 10 pieces out of boards, the convex die-holder t , in combination with the feed-roller pairs $r r'$ and $s s'$, the cheek-plates $u v$, and the upper dies $x x'$, substantially as shown and described, and for the purpose set forth.

15 2. In a machine for cutting wedge-shaped pieces out of boards, the combination of the plungers k and l , carrying the upper dies $x x'$, with a double crank-shaft d , the oppositely-placed cranks f and g , and with the convex

die-holder t , substantially as shown and de- 20 scribed, and for the purpose set forth.

3. In a machine for cutting wedge-shaped pieces out of boards, the plungers k and l , connected to a double crank-shaft d , the cranks f and g of which are oppositely arranged, in 25 combination with feed-roller pairs $r r'$ and $s s'$ moving simultaneously, and with the friction-wheels o and n , of which the latter at each revolution actuates the former only for a short distance, working together and constructed substantially as shown and described, and for the purpose set forth.

This specification signed by me this 5th day of November, 1889.

GUSTAV A. ONCKEN.
